UNITED STATES PATENT OFFICE.

FRANK J. MYNAR AND CHARLES P. ZIMMERMAN, OF BANTONAGE, MARYLAND.

SHIRT.

1,127,075.

Specification of Letters Patent.

Patented Feb. 2, 1915.

Application filed May 6, 1913. Serial No. 785,848.

To all whom it may concern:

Be it known that we, FRANK J. MYNAR and CHARLES P. ZIMMERMAN, citizens of the United States, residing at Baltimore, in the 5 State of Maryland, have invented certain new and useful Improvements in Shirts, of which the following is a specification.

This invention relates to improvements in shirts, and has for one of its objects the 10 provision of means for preventing the facings of a shirt, which carries the buttons and button-holes, and other fastening means, from buckling near the neckband of the shirt.

Another object of this invention is the 15 provision of means which will prevent the front collar-button, used in attaching a collar to the shirt, from being bent at an angle and irritating the neck of a wearer when 20 the collar is of a smaller size than the neckband of the shirt.

A still further object of this invention is the provision of a means of the above described nature which will prevent the base 25 of the collar-button from contacting with the neck of the wearer.

With the foregoing and other objects in view, this invention consists of such novel features of construction as will be herein- 30 after more fully described, illustrated in the accompanying drawings and claimed.

In describing the invention in detail, reference will be had to the accompanying drawings wherein like characters of reference designate like or corresponding parts throughout the several views, and in which,

Figure 1 is a view of a fragment of a shirt showing the invention applied thereto; Fig. 2 is a view similar to Fig. 1 only looking at the shirt from a different point of view, and showing the invention in a different position; Fig. 3 is a cross-sectional view through the facing of the shirt which carries the buttons and through a portion 45 of the invention showing the means for preventing the base of the collar-button from contacting with the neck of the wearer. Fig. 4 is a detail sectional view through the facing of the shirt which carries the button and also through a portion of the invention illustrating the manner in which the facing of the shirt buckles near the neck-band when the flap is not connected thereto.

In referring to the drawings by numeral, 55 1 designates a shirt of any construction hav-

ing the facings 2 and 3 formed adjacent the edges of the split portion of the shirt. The facing 2 carries the buttons (not shown) and the facing 3 the button-holes 4 by means of which the opening in the shirt is closed or the same is fastened upon the body of the wearer. The shirt has a neckband 5 formed thereupon the outer portion of which is of the usual construction employed in neckbands for shirts.

Secured to the inner side of the neckband 5 is a reinforced strip of material 6 which entirely covers the interior of the neckband 5, and which has a flap 7 formed integrally with one end thereof. The upper end 8 of the flap 7 is securely sewed to the neckband 5 as is the outer edge 9 for a short distance, extending downwardly from the upper edge of the same. The greater portion of the flap 7 and that which extends downwardly from the strip 6 is loose or unattached to any portion of the shirt, as is clearly shown in Fig. 1 of the drawings, and has a button 10 sewed upon the inner side 80 near the lower end of the same. The button 10 is received by the button-hole 11 which is formed in the facing 2 of the shirt, which facing carries the buttons (not shown) of the fastening means of the shirt.

By inserting the button 10 through the buttonhole 11 and holding the flap 7 adjacent the inner side of the facing 2, a reinforcement for the upper portion of the facing 2 is provided, which reinforcement will prevent the upper portion of the facings 2 and 3 from buckling when the two facings of the shirt are fastened together.

By sewing the upper end 8 of the flap 7 and the side 9 of the same securely to the neckband a pocket or recess 12 is formed between the upper end of the flap 7 and the neckband 5, as is clearly shown in Fig. 3 of the drawings. This pocket is directly back of the button-hole 13 through which a collar-button 14 is inserted for attaching a collar to the shirt. By the provision of the pocket or recess 12 the base 14' of the collar-button 14 will be prevented from contacting with the neck of the wearer, as a portion of the flap 7 will be disposed between the base 14' and the neck of the wearer (not shown), as will be clearly seen by referring to Fig. 3 of the drawings.

By the provision of the pocket or recess 110 12 and of the portion of the flap 7 which engages the base 14' of the collar-button, the

latter will also be prevented from bending or turning at an angle when a collar is attached to the shirt which collar is of a smaller size than the neckband of the shirt.

5 In Fig. 4 of the drawings a sectional view through the facing or marginal edge of the shirt, which carries the buttons of the same, and through the flap 7, is shown. This view illustrates the manner in which the 10 facing or marginal edge of the shirt buckles near the neck-band of the same when the flap 7 is not connected thereto by means of the button 10 and the button-hole 11. The buckling of the shirt is designated by the 15 numeral 15. When the strip 7 is secured or attached to the facing or marginal edge 2 of the shirt, by means of the button 10 and the button-hole 11, the flap rests against the inner surface of the facing or marginal 20 edge 2, and tends to impart a downward pulling motion, which is generated by the insertion of the shirt into the trousers of the wearer, (not shown), so that the facing or marginal edge 2 of the shirt will be held 25 perfectly straight and prevented from buckling, as is shown at 15.

In practical fields certain minor features of construction may necessitate alterations to which the patentees are entitled provided 30 such alterations are comprehended within the scope of what is claimed.

What is claimed is:

1. The combination with a shirt having a neck-band and facings upon its marginal

edge provided with means for fastening the 35 shirt upon the body of a wearer, of a flap secured to the neck-band of the shirt co-acting with a part of said fastening means for preventing said facings from buckling near said neck-band. 40

2. The combination with an open shirt having a neck-band and means carried by the marginal edges of the shirt for fastening the same upon the body of a wearer, of a flap secured to the shirt near the neck- 45 band thereof and extending downwardly inside one of the marginal edges, and means carried by said flap for co-acting with said fastening means at a point below said neck-band to prevent the buckling of said marginal edge. 50

3. As a means to prevent the buckling of the facings of a shirt, a neck-band portion for the shirt, a flap integrally incorporated in the structure of the neck-band and having a free end depending inside of the facing upon one of the marginal edges of the shirt, and means for attaching said free end to said marginal edge to prevent the buckling of the latter. 55

In testimony whereof we affix our signatures in presence of two witnesses.

FRANK J. MYNAR.
CHARLES P. ZIMMERMAN.

Witnesses:

AUGUSTUS W. BRADFORD,
ALLAN C. THURMAN.
